DESIGN FOR A PIANO ACCORDION TREBLE MECHANISM COVER

Maurice H. Berlin, Chicago, Ill., assignor to Chicago Musical Instrument Company, Chicago, Ill., a corporation of Illinois

Application June 15, 1936, Serial No. 63,299

Term of patent 7 years

To all whom it may concern:

Be it known that I, Maurice H. Berlin, a citizen of the United States, residing at Chicago, in the county of Cook and State of Illinois, have invented a new, original, and ornamental Design for a Piano Accordion Treble Mechanism Cover, of which the following is a specification, reference being had to the accompanying drawing, forming part thereof.

In the drawing:

Fig. 1 is a front elevation of a piano accordion

treble mechanism cover showing my new design.

Fig. 2 is a vertical sectional view on an enlarged scale taken in the plane of the line indicated at 2 on Fig. 1.

Fig. 3 is a horizontal sectional view on an enlarged scale taken in the plane of the line indicated at 3 on Fig. 1.

I claim:

The ornamental design for a piano accordion treble mechanism cover, as shown.

MAURICE H. BERLIN.
